TOWEL CABINET

Edward T. Hails, Coral Gables, Fla.

Application May 18, 1929, Serial No. 364,209
Renewed May 8, 1934

3 Claims. (Cl. 312—37)

The present invention relates to towel cabinets from which individual towels are dispensed and embodies, more specifically, an improved form of towel cabinet in which the operating mechanism is simple in construction and effectively functions to return a used towel automatically into the towel cabinet. Such return is slow initially, and is accelerated after a desired period of time within which the average 5 user will complete the wiping operation. In this manner, ample time is afforded the user to complete the wiping operation and the towel will not be pulled away from him during actual use thereof. The means for providing access to 10 the towels, after being actuated, affords a positive return for the soiled towel and insures the quick and effective disappearance of soiled towels.

An object of the present invention, accordingly, is to provide a towel cabinet which is manually operated to provide a potential towel returning force which functions after the towel has been used.

A further object of the invention is to provide a towel cabinet in which the towel returning force is retarded sufficiently to afford adequate time for using the towel before the returning force becomes effective.

A further object of the invention is to provide a towel cabinet of the above character in which the towel returning force is retarded during an initial period, and accelerated during a final period for returning the towel quickly to the cabinet for use.

A further object of the invention is to provide an improved towel supporting means, and means for freeing the edge of a towel from its pack to facilitate the exposing thereof.

A further object of the invention is to provide an improved towel supporting means within a towel cabinet of the above character.

Further objects of the invention will be apparent as it is described in greater detail in connection with the accompanying drawings, wherein:

Figure 1 is a view in front elevation showing a towel cabinet constructed in accordance with the present invention.

Figure 2 is a view similar to Figure 1, showing the operating means actuated to expose the towel and enable it to be pulled out ready for use.

Figure 3 is a view similar to Figure 1, showing 55 the front of the cabinet swung through 180°

to expose the operating mechanism and contents of the cabinet.

Figure 4 is a view in section taken on line 4—4 of Figure 1, and looking in the direction of the arrows.

Figure 5 is a view similar to Figure 4, showing the operating knob elevated in the position shown in Figure 2, a towel having been pulled through the opening ready for use.

Figure 6 is a perspective view showing the rear 10 plate of a towel clamp constructed in accordance with the present invention.

Figure 7 is a view similar to Figure 6 showing a front plate of the towel clamp.

Referring to the above drawings, *a* designates 15 a suitable cabinet having a front cover *a'* which may be secured in a closed position to the cabinet by a suitable securing means *a''*. Depending hooks *a'''* are provided in the cabinet from which the towel clamp is suspended.

If desired a mirror *a⁴* may be provided on the outer face of the cover *a'* and an aperture *a⁵* is formed in the cover through which one may reach to grasp a towel. A vertical groove *a⁶*, formed in the cover *a'*, serves as a guide for the 25 operating knob *b'* of a weight *b*.

At the upper portion of the cabinet, between the cover and the top of the cabinet, an elongated aperture *a⁷* is provided through which the weight *b* may pass when it is elevated by moving 30 the knob *b'* to the position shown in Figure 2.

The weight *b* rides in grooves formed by retaining flanges *a⁸* on the cover *a'* and is formed with an aperture *b²* which aligns with aperture *a⁵* when the knob is in the position shown in 35 Figure 2. In this position, a front edge of a towel is exposed for use and the towel may be pulled out by reaching through the aligned apertures and pulling the edge thereof as shown in Figure 5. Adjacent the upper edge of the aperture *b²*, the weight *b* carries an inwardly extending lip *b³* which engages the edge of the foremost towel of the pack and frees it from the pack, thus facilitating the grasping of the 40 towel by the user.

A bracket *a⁹* is mounted on one side of the cabinet *a* and is formed with spaced semi-circular flanges *a¹⁰*, between which a semi-circular groove is provided. In order to retard the downward movement of the weight *b*, a counterweight *c* is provided. This counterweight is connected to the weight *b* by a strap *d*. In the preferred form, the groove between the flanges *a¹⁰* is formed of metal and the strap *d* is also formed of metal. Connecting the strap *d* to an eye *b⁴* 50

on the weight b , is a leather strap e . It will be understood, of course, that the coefficient of friction between leather and metal is greater than that between metal and metal. In view of this fact, therefore, movement of the weight c during the period that the leather strap e rides over the metal bracket is slower than when the metal strap d rides over the metal bracket. Proper selection of materials, radius of curvature of the groove on the bracket a^9 , and weight of counterweight c , will provide the time intervals found most desirable for these successive periods of operation.

It is preferred that the towels be secured together as by sewing along corresponding adjacent edges of the towels, thus forming in effect, a book of towels. Each towel h is doubled back upon itself and the successive towels overlie each other as clearly shown in Figure 4. In this position they are clamped by means of front and back plates f and g , respectively. Elastic bands g' are secured to the back plate g and engage keepers g^2 . These keepers are notched at g^3 to engage pins f' on the front plate f . The front plate is further provided with apertures f^2 which engage the hooks a^3 and suspend the book of towels in an inverted position in the cabinet. The towel engaging surface of the back plate g is roughened, as indicated at g^4 to prevent the book of towels from slipping between the plates.

A metal rod i passes through a loop provided in the connected ends of the towels and this rod is carried in suitable notches a^{11} formed at the sides of the towel cabinet. After being used, the towels fall down within the cabinet as shown in Figure 4 and after all of the towels have been used, they are suspended from the rod i in a manner which will be quite apparent. Projecting shoulders a^{12} engage the forward lower portions of the book of towels at either side thereof and thus serve as a reenforcement for preventing more than one towel from being removed at a time when the book is large.

In order that suitable advertising may be displayed when a towel is being used, a frame j is provided with a rearwardly extending flange j' which is engaged by the upwardly moving edge of the weight b and elevated to the position shown in Figure 5. Suitable advertising indicia may be applied to the front face of the frame j and thus automatically displayed as the towel is used. On the forward face of the weight b ,

clips b^5 are provided for receiving additional advertising matter k . When the knob is raised to the position shown in Figures 3 and 5, the advertising matter k is above the opening a^5 but, as the weight drops, the advertising matter is displayed through the opening.

From the foregoing description, it will be apparent that the rear plate of the towel clamp follows the pack and advances toward the front plate as the towels are withdrawn and used. The front plate stays in place and thus always provides a free edge of a towel adjacent the opening a^5 .

While the invention has been described with specific reference to the construction shown in the accompanying drawings, it is obvious that modifications and changes in design and the arrangement of parts may be made without departing from the scope of the present invention as defined in the appended claims.

I claim as my invention:

1. In a device of the character described having a cabinet adapted to receive a plurality of towels and a weighted closure thereon adapted to be moved to expose a towel for use, a counterweight in the cabinet, a strap connecting the counterweight to the weighted closure, said strap including a metallic portion and a leather portion, and a non-rotatable metallic friction surface in the cabinet over which the portions pass.

2. In a device of the character described having a cabinet adapted to receive a plurality of towels and a weighted closure thereon adapted to be moved to expose a towel for use, a counterweight in the cabinet, means connecting the counterweight to the weighted closure, said means having portions, the coefficients of friction of which differ, and a non-rotatable surface in the cabinet over which the connecting means passes.

3. In a device of the character described having a cabinet adapted to receive a plurality of towels, manually operated means to expose a towel for use and return a used towel into the cabinet, means operable upon exposing a towel for use to control the action of the last named means, said means comprising means whereby the operation of the first named means is slow at first and more rapid after a predetermined time.

EDWARD T. HAILS.
